UNITED STATES PATENT OFFICE.

JOHN J. MCPHERSON, OF MONTGOMERY, ALABAMA.

DESIGN FOR AN INHALER.

SPECIFICATION forming part of Design No. 34,779, dated July 16, 1901.

Application filed April 29, 1901. Serial No. 58,092. Term of patent 7 years.

To all whom it may concern:

Be it known that I, JOHN J. MCPHERSON, a citizen of the United States, residing at Montgomery, in the county of Montgomery and State of Alabama, have invented and produced a certain new and original Design for Inhalers; and I do declare the following to be a full, clear, and exact description of the invention, such as will enable others skilled in the art to which it appertains to make and use the same.

The invention relates to a new and original design for an inhaler; and it consists of the design of the configuration shown in the accompanying drawing, in which I have illustrated the invention in perspective.

The leading feature of the design comprises

two cylindrical shells *a* and *b* of different diameters, one located within the other and projecting outwardly a slight distance beyond the edge thereof, and each of which is provided with oppositely-projecting hollow truncated conical extensions *c* and *d*.

What I claim is—

The design for an inhaler, as herein shown and described.

In testimony whereof I have hereunto set my hand in presence of two subscribing witnesses.

JOHN J. MCPHERSON.

Witnesses:

W. M. BLAKEY;
B. GASTON.
